Fig. 3.

UNITED STATES PATENT OFFICE.

FRED E. BRIGHT, OF PHILADELPHIA, PENNSYLVANIA.

CHUCK.

1,256,104.

Specification of Letters Patent. Patented Feb. 12, 1918.

Application filed May 3, 1917. Serial No. 166,037.

To all whom it may concern:

Be it known that I, FRED E. BRIGHT, a citizen of the United States, residing at Philadelphia, in the county of Philadelphia and State of Pennsylvania, have invented certain new and useful Improvements in Chucks, of which the following is a specification, reference being had therein to the accompanying drawing.

10 This invention relates to work holding chucks, and has reference more particularly to chucks adapted to grip the work externally in order that annular work pieces such as rings, cylinders and the like may be held 15 so that the inner surfaces thereof may be subjected to grinding, forming, finishing or like operations.

The aim of the invention is to produce a chuck of this type which will be simple and durable in construction and which may be conveniently operated to grip the work with powerful force and hold the same without liability of displacement, and with this end in view my invention consists of a chuck 25 comprising the novel features of construction and improved arrangement of parts described in the specification to follow, and the novel parts of which will be set forth in the appended claims.

30 In the accompanying drawings:

Figure 1 is a front face view of my improved chuck showing a work piece in the form of a ring held thereby, the said work piece being broken away to expose other 35 parts to view.

Fig. 2 is a longitudinal sectional elevation through the same, the work piece being omitted and certain parts being broken away to better illustrate the construction.

40 Fig. 3 is a perspective view of the movable gripping jaw, its stem or carrier, and the operating plunger by which the jaw is moved, said parts being shown separated from each other.

45 Fig. 4 is a central longitudinal sectional elevation through the operating plunger.

Referring to the drawings:

My improved chuck comprises a body 1 of circular disk-like form, a fixed supporting 50 jaw 2 secured to the face of the body, an opposing gripping jaw 3 sustained by the body and movable to and from the fixed jaw to respectively grip and release the work, and an operating member 4 sustained by the

body and engaging the movable jaw to actuate the same.

The fixed jaw is in the present instance in the form of a flat plate having its inner edge formed with a work seat 2^a curved inwardly from a center coincident with the longitudinal axis of the chuck, against which work seat the outer curved surface of the work piece, in the present instance the ring A, is adapted to bear, the said seat being provided on its inner edge with a radially extending annular shoulder 2^b which supports the inner side of the ring. The jaw is seated flatly against the face of the chuck body and is detachably connected thereto by means of fastening screws 2^c extending through slots 2^d in the jaw and screwed into the chuck body, whereby the jaw may be adjusted in position so that it may be reset and properly centered when occasion requires, and may be removed for grinding or 75 for the substitution of jaws of other sizes, to hold work pieces of different diameters.

The movable jaw 3 comprises a jaw proper 3^a and a carrier or stem 3^b to which the jaw proper is detachably connected by means of a 80 fastening screw 3^e extending through a slot 3^d in the jaw proper and screwed into the same; whereby the jaw is removable and adjustable similar to the fixed jaw, and for like purposes. The stem 3^b extends radially of 85 the chuck body and is mounted to move radially thereof in an open radial guiding slot 1^a in the front portion of the chuck body, which slot extends from one edge of the body across the center thereof and terminates inward of the opposite edge. The slot is undercut to receive guiding ribs 3^e extending outwardly from the stem, and the latter is formed on its end with a forwardly extending lug 3^f which overlies and forms a bearing for the upper edge of the jaw proper.

The jaw proper has its inner edge formed with a work seat 3^g, curved from a center coincident with the axis of the chuck, and adapted to bear against the outer curved 100 surface of the work piece, a radial shoulder 3^h being formed on the inner side of the seat to bear against the inner side of the ring.

From the construction described it will be seen that the work piece, resting on the work seat of the fixed jaw, may be firmly gripped and held in fixed position by moving the movable jaw inwardly toward the fixed jaw

so that the inner side of the ring will be exposed and may be subjected to forming, grinding, finishing and like operations, and by moving the movable jaw outwardly away from the fixed jaw the work will be released and may be freely removed.

The operating member 4 for moving the movable jaw inwardly to grip the work, consists of a cylindrical plunger 4^a mounted 10 to move axially of the chuck in a central axial opening 5 in the chuck body, the end of the plunger being formed with an open slot 4^b, the inner walls of which are flat and parallel to each other. This slot receives 15 the central portion of the stem 3^b of the movable jaw, which stem is reduced at this point and formed with flat parallel side faces 3^c which, in the axial movements of the plunger, bear flatly against the walls of 20 the slot. One of the walls of the slot is provided with a groove 3^d inclined relatively to the axis of movement of the plunger, which groove receives a rib 2^e projecting outwardly from the side face of the stem 25 and inclined similar to the groove, the groove and rib thus forming wedging surfaces which, when the plunger is moved axially relatively to the stem, will coöperate with each other and will positively move 30 the stem radially inwardly or outwardly according to the direction of movement of the plunger. In the form of the parts shown the jaw will be moved inwardly to grip the work when the plunger is retracted, and 35 will be moved outwardly to release the work when the plunger is advanced. But these motions may be reversed by changing the inclination of the groove and rib. The lower edges of the slotted end of the plunger are formed with inclined recesses 3^f which receive correspondingly inclined shoulders 2^f on opposite sides of the stem, which recesses and shoulders coöperate with 40 each other in assisting in the guiding of the plunger in its axial movements, and avoids liability of the parts to bend. The movement of the plunger may be effected by any appropriate means and in any appropriate 45

manner, but as such means constitute no part of the present invention they have not 50 been illustrated herein.

In the foregoing description and accompanying drawings I have set forth my invention in the particular detailed form which I prefer to adopt and which in practice has been found to answer to an admirable degree the objects to be attained. It will be manifest, however, that these details may be variously changed and modified without departing from the limits of my invention; and it will be understood that the invention is not limited to any particular form or construction of the parts except in so far as such limitations are specified in the claims.

Having thus described my invention, what I claim is:

1. In a chuck, the combination of a body, a gripping jaw having a radial stem mounted in said body and movable inwardly and outwardly to correspondingly move the gripping jaw, and an axially movable operating member provided with a slot embracing the radial stem, the wall of said slot and side of the stem being so relatively 75 formed that the stem will be moved radially in the axial movements of the plunger.

2. In a chuck, the combination of a body having a radial guiding opening therein, a work supporting jaw sustained by the body, 80 a gripping jaw having a radial stem mounted in said guiding opening and movable inwardly and outwardly to carry the gripping jaw respectively to and from the supporting jaw, and an axially movable operating member provided with a slot embracing the radial stem, the wall of the slot and the side of the same being provided with coöperating surfaces inclined relatively to the movement of the operating member, and adapted, in the movements of the operating member, to move the jaw inwardly and outwardly respectively.

In testimony whereof, I have affixed my signature.

FRED E. BRIGHT.
